US00D821894S

(12) **United States Design Patent** (10) Patent No.: **US D821,894 S**
Verity et al. (45) Date of Patent: ** Jul. 3, 2018

(54) **HANDHELD DETECTOR DEVICE**

(71) Applicant: **FLIR Detection, Inc.**, Stillwater, OK (US)

(72) Inventors: **Jeffrey A. Verity**, Knoxville, TN (US); **Steve W. Fleetwood**, Oak Ridge, TN (US); **Zhenmei Mao**, Shanghai (CN); **Xuan Song**, Jiangsu (CN)

(73) Assignee: **FLIR Detection, Inc.**, Stillwater, OK (US)

(**) Term: **15 Years**

(21) Appl. No.: **29/588,406**

(22) Filed: **Dec. 20, 2016**

(51) LOC (11) Cl. **10-07**

(52) U.S. Cl.

USPC **D10/46**

CLAIM

The ornamental design for a handheld detector device, as shown and described.

DESCRIPTION

FIG. 1 is a front-left-bottom perspective view of a handheld detector device embodying the new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a front-right-top perspective view thereof.

The broken lines in the figures depict portions of the handheld detector device and form no part of the claimed design.

1 Claim, 8 Drawing Sheets
